(57) **CLAIM**

The ornamental design for a tattoo grip, as shown and described.

DESCRIPTION

FIG. 1 is a top perspective view of a tattoo grip, showing a first embodiment of my new design.

FIG. 2 is a right side elevational view thereof.

FIG. 3 is a left side elevational view thereof.

FIG. 4 is a back view thereof.

FIG. 5 is a front view thereof.

FIG. 6 is a top plan view thereof.

FIG. 7 is a bottom plan view thereof.

FIG. 8 is a top perspective view of a tattoo grip, showing a second embodiment of my new design.

FIG. 9 is a top perspective view of a tattoo grip, showing a third embodiment of my new design.

FIG. 10 is a right side elevational view thereof.

FIG. 11 is a left side elevational view thereof.

FIG. 12 is a back view thereof.

FIG. 13 is a front view thereof.

FIG. 14 is a top plan view thereof.

FIG. 15 is a bottom plan view thereof.

FIG. 16 is a top perspective view of a tattoo grip, showing a fourth embodiment of my new design.

FIG. 17 is a top perspective view of a tattoo grip, showing a fifth embodiment of my new design.

FIG. 18 is a right side elevational view thereof.

FIG. 19 is a left side elevational view thereof.

FIG. 20 is a back view thereof.

FIG. 21 is a front view thereof.

FIG. 22 is a top plan view thereof.

FIG. 23 is a bottom plan view thereof; and,

FIG. 24 is a top perspective view of a tattoo grip, showing a sixth embodiment of my new design.

The broken lines showing tattoo tubes are for the purpose of illustrating environmental structures and form no part of the claimed design.

1 Claim, 24 Drawing Sheets
